UNITED STATES PATENT OFFICE.

HARRY LANDSIEDEL, OF CINCINNATI, OHIO, ASSIGNOR TO THE DALTON ADDING MACHINE COMPANY, OF CINCINNATI, OHIO, A CORPORATION OF OHIO.

RECORDING-MACHINE.

1,321,648.

Specification of Letters Patent. Patented Nov. 11, 1919.

Application filed April 21, 1919. Serial No. 291,618.

To all whom it may concern:

Be it known that I, HARRY LANDSIEDEL, a citizen of the United States, residing at Cincinnati, county of Hamilton, and State of 5 Ohio, have invented a new and useful Recording-Machine, of which the following is a specification.

This invention relates to recording machines.

10 The invention has particular reference to mechanism for shifting the paper carriage of the recording machine alternately in opposite directions to different adjusted positions, in order to permit the recording mechanism to record items in parallel vertical columns; such recording being performed by recording items alternately in the different columns thus, in a general sense, recording items in a number of vertical columns concurrently.

15 The invention also includes mechanism operating, as an incident to shifting of the paper carriage to one of its adjusted positions, to disable the adding mechanism of 25 the machine. In the form of the invention shown the adding mechanism is disabled by connections operated by the paper carriage to retain the adding mechanism out of operative engagement with the actuating racks, 30 so that said racks are free to operate in accompaniment with the recording mechanism without disturbing or operating the adding mechanism. As a result of this construction one of the vertical columns of items 35 listed will not be added.

20 The usual line space mechanism of the machine is controlled so that the respective items of the different columns may be recorded in the same horizontal lines. In the 40 operation of the machine an item is recorded in one column and the paper carriage is shifted laterally to present another column in position to have an item or number recorded therein; and the line space mechanism is held inoperative during this lateral movement of the paper carriage. As a result of this construction and operation the respective numbers in the different columns are printed on the same horizontal lines. 45 However, as an incident to the recording of the number in the last column in which numbers are recorded, the line space mechanism is operated to feed the paper in line spacing so that as an incident to movement of

the paper carriage to its initial columnar 55 position the paper is moved to present another line for reception of a number in the first column.

In the particular embodiment of the invention shown it is embodied within a Dalton adding machine, though it will be apparent that the use of the invention is not restricted to a Dalton machine, and that the invention may with equal advantage and adaptability be embodied in various types 60 65 of recording machines.

In the accompanying drawings, in which the invention is shown—

Figure 1 is a sectional view of a Dalton adding machine illustrating the invention 70 mounted therein and connected with the paper carriage of the machine for moving the paper carriage alternately in opposite directions to different columnar positions.

Fig. 2 is a plan view of the invention. 75

Fig. 3 is an enlarged detail view of a part of the mechanism included in the present invention.

Fig. 4 is a view of a part of the connections operated by the paper carriage in one 80 position thereof to disable the adding mechanism. This view shows the connections in the positions to which they are operated by the paper carriage.

Fig. 5 is a view showing the position of 85 a part of the connections when the paper carriage is in position to permit the adding mechanism to function.

Fig. 6 is a view illustrating the devices controlling the operation of the line space 90 mechanism.

Fig. 7 is another view of the devices controlling the operation of the line space mechanism.

As shown in the drawings and as is well 95 known the Dalton machine includes a laterally movable paper carriage 1 containing a platen 2 around and upon which the paper is supported in position to receive records from the printing type. The type 3 of said 100 machine are mounted on type-carriers and are operable thereby to record the desired items upon the paper in the paper carriage. The paper carriage is supported by and movable laterally upon a track or rail 4. 105 My present invention comprises mechanism for moving the paper carriage laterally in alternately opposite directions in order to

present different vertical columns of the paper in position to receive the records produced by operation of the type.

As shown, the paper carriage contains a rod 5 supporting a sleeve 6, said sleeve being provided with a pair of arms 7. A lever 8 has one end mounted on a pivot 9 and the opposite end extending between the arms 7; so that the paper carriage may be moved laterally in alternate opposite directions to different adjusted positions by operation of said lever; and the paper carriage will be held in adjusted positions in which it is placed by said lever.

15 A link 10 pivotally connects the lever 8 with an arm 11 attached to the upper end of a revolute shaft 12. A pinion 13 is attached to the lower end of the shaft 12 and meshes with a large gear 14. A disk 15 is rigid with the gear 14 and has a number of notches 16 formed in the periphery thereof. A lever 17 has one end pivoted upon the axis of the gear 14 and the disk 15, and its opposite end supporting a pawl 25 or detent 18 having a tooth or projection 19 arranged to engage successively in the notches 16 when the lever 17 is operated and thereby rotate the gear 14 and the shaft 12, with the result that the paper carriage will 30 be shifted laterally in alternate opposite directions to present different columns of the paper successively to the recording mechanism.

A spring 20 connects the free end of the pawl 18 with the lever 17 and thereby holds the pawl in contact with the disk 15. Due to the proper inclination of the rear walls of the notches and the rear wall of the tooth 19, said tooth will ride out of the 40 notch in which it is engaged when the lever 17 is moved rearwardly. That is, rearward movement of the lever 17 and the pawl 18 does not turn the gear 14, but only moves the pawl to position to engage the 45 tooth 19 in the next adjacent notch 16. Then, upon forward movement of the lever 17, the pawl being in engagement with the disk 15 will turn said disk and thereby the gear 14 a distance sufficient to turn the 50 shaft 12 through one half of a revolution. That is, such operation of the lever 17 and the pawl 18 turns the shaft 12 and thereby the arm 11 successively from the position shown in Fig. 2 to a position in which 55 the arm 11 extends in a diametrically opposite position; and the next operation of the lever 17 and the pawl 18 turns the shaft 12 and the arms 11 to the position in which they are shown in Fig. 2. Thus, the paper 60 carriage is moved in the manner above described.

The shaft 12 is equipped with a detent device for holding the same against accidental rotation and to resist the tendency 65 to turn the shaft when the lever 17 and

the pawl 18 are moved rearwardly. Said detent device includes a disk 21 having two diametrically opposite notches 22 formed in its periphery in position to be engaged by a roller 23 mounted on a lever 24. A spring 70 25 draws the lever 24 toward the disk 21 to engage the roller 23 in said notches. Thus, the detent roller is engaged in the notches 23 and the shaft 12 will be restrained from accidental turning.

It is well known that the Dalton and other machines include a controlling rock shaft 26. In the present embodiment of the invention the rock shaft 26 is utilized to operate the carriage shifting mechanism. 80 As shown the shaft 26 has an arm 27 attached thereto provided with a pin 28 extending into a slot 29 in a lever 30. The lever 30 is pivoted upon a support 31. As a result of this arrangement the lever 30 85 is oscillated at each operation of the main rock shaft 26. A link 32 has its rear end connected with the lever 17 through the medium of a connecting link 33 and its forward portion provided with a notch 34 90 adapted to receive a pin 35 extending laterally from the upper portion of the lever 30. When the shaft 26 is turned in a forward direction the upper end of the lever 30 is moved rearwardly thereby actuating 95 the link 32 and also the lever 17 as required to move the pawl 18 to position to engage the next adjacent notch 16 in the disk 15. As the shaft 26 is returned to its initial or starting point the upper end of the lever 100 30 is moved forwardly thereby through the connections described, causing the pawl 18 to turn the gear 14, with the result that the paper carriage is moved laterally to a different adjusted position as described. The 105 link 32 is drawn downwardly by a spring 36.

From the foregoing it will be understood that on each operation of the rock shaft 26 the paper carriage is moved from one position to another and that such movement is 110 in alternate opposite directions. Such movement of the paper carriage is incidental to and occurs as a direct result of operation of the rock shaft. On some occasions it is desirable to print or list items in 115 a single vertical column and to prevent lateral shifting of the paper carriage after each item is listed. Since the shifting of the paper carriage is effected because of the connection between the link 32 and the lever 120 30, it is only necessary to disconnect said link 32 from said lever 30 in order to enable the recording mechanism of the machine to operate without lateral movement of the paper carriage. For the purpose of disconnecting the link 32 from the lever 30 a lever 37 is provided, the same being pivoted upon a support 38 and having a lateral projection 39 on its lower end extending under the link 32. Another arm 40 of the 125 130

lever 37 terminates adjacent to the inner extremity of a stem 41. The stem 41 extends through a slot in the case of the machine and the inner portion thereof extends 5 through and is supported within a slot in a bracket 42. Outward movement of the stem 41 is limited by a lateral extension 43 on the inner end of the stem, the same being arranged to contact with the bracket. The 10 stem 41 has a finger button 44 on its outer end whereby the stem may be conveniently operated. When the stem 41 is pressed inwardly the lower end of the lever 37 is raised a sufficient distance to lift the link 32 out of engagement with the projections 35, thus leaving the lever 30 free to operate while disconnected from the link 32. Thus the recording mechanism of the machine may be operated without moving the paper 15 carriage from the adjusted position in which it is placed before the stem 41 is pressed inwardly. The stem 41 may be latched in its inner position, the same being provided with a notch 45 adapted to engage 20 with the case of the machine. When the stem 41 is disengaged it will be moved outwardly by the pressure of the lever 37-40 actuated by the link 31 under impulse of the spring 36.

30 In the embodiment of the invention shown, the adding mechanism of the machine is held inoperative and is prevented from adding the numbers listed in one of the vertical columns. As shown, one of the 35 frame members 46 (Fig. 4) of the paper carriage is formed with a shoulder or cam 47 which, in one of the columnar positions of the paper carriage, engages a roller 48 carried by the upper end of a lever 49. The 40 lever 49 is pivotally supported upon a shaft 50 and extent of movement thereof is limited by a pin 51 extending into a hole 52 in the lever. The lower end of the lever 49 has pin-in-slot connection 53 with a link 54, 45 thus permitting limited relative movement between the lever 49 and said link. A retractile spring 55 connects the lower end of the lever 49 with the rear end of the link 54, said spring tending to hold the lever 50 and the link in the relative positions shown in Fig. 5. A spring 56 connects the lever 49 with a part of the frame of the machine and is operative to draw said lever to its 55 idle position when the paper carriage is moved to disengage the shoulder 47 from the roller 48.

Referring now to the adding mechanism of the Dalton adding machine, it is well known that the same comprises adding pinions 57 supported on a shaft 58 mounted in, and operable by a frame 59 as required to move the adding pinions into and out of mesh with the actuating racks 60. In the Dalton adding machine the frames 59 are 65 moved as required to engage the adding

pinions with the racks 60 and to disengage said pinions from said racks by a link 61 operated in a well known manner by a device 62 carried by a rock shaft 63. It is unnecessary in connection with my present 70 invention to describe in detail the manner in which the device 62 actuates the link 61 first in one direction as required to disengage the adding pinions from the racks, and then in the opposite direction to engage said 75 pinions with the racks, and it is sufficient for present purposes to understand and to assume that such operation, in fact, is effected. The opposite end of the shaft 63 in the Dalton machine has attached thereto a 80 plate 64 and pivotally supports a lever 65 having a pin 66 engaging in a notch in the plate 64, thus limiting movement of said lever 65 relative to said plate. The lower portion of the lever 65 carries a roller 67 85 which is engaged by a plate 68 on the shaft 26 when said shaft is turned in a forward direction, as required to turn the shaft 63 and cause the device 62 to effect disengagement of the adding pinions from the racks. 90 As the plate 68 starts to return toward its initial position or starting point it engages the roller 67 and turns the shaft 63 in a direction to cause the device 62 to effect engagement of the adding pinions 57 with the 95 racks 60, thus enabling said racks to operate the adding pinions during the return movement of the racks. This construction and this operation thereof under control of the main rock shaft 26 of the Dalton machine is well known and requires no further or extended explanation.

100 My present invention utilizes the link 54 to move the lever 65 to position to prevent operation thereof by the plate 68 during return movement of said plate, thus preventing said plate from turning the shaft 63 which would result in reengagement of the adding pinions with the racks 60. As shown, the lever 65 is extended and has pin-in-slot connection 69 with the link 54. The 105 length of the slot 69 is such that when the link 54 is in its forward position to which it is actuated by the spring 55, the rear end of the slot engages the pin 69 and actuates the 110 lower end of the lever 65 forwardly to hold the roller 67 out of the path of movement of the plate 68. This leaves the plate 68 free to return to its starting point without engaging the roller 67 and therefore leaves 115 inoperative the mechanism for moving the adding pinions into and out of engagement with their actuating racks.

120 When the paper carriage is shifted to another columnar position the shoulder 47 is released from the roller 48, whereupon the spring 56 withdraws the lever 49 and said lever withdraws or actuates rearwardly the link 54, due to the fact that the pin 53 engages the rear wall of the slot through 130

which it extends and thereby moves said link.

The slot 69 is of sufficient length to permit free movement of the lever 65 by the plate 68 without moving or disturbing the link 54 when the paper carriage is in position to permit functioning of the adding mechanism.

As mentioned in the statement of the nature of the invention the line space mechanism is controlled so that it will not operate to move the paper after the recording of a number in the first column, but is rendered inoperative in order to permit the 15 paper carriage to move to position so that the corresponding item in the next column will be recorded on the same horizontal line as the item recorded in the first column. The line space mechanism includes a ratchet 20 wheel 70 (Figs. 6 and 7) attached to the platen shaft 71. A rod 72 is supported by the paper carriage for rocking movements and at one end thereof adjacent to the wheel 70 a lever 73 is attached. A pawl 74 25 is pivotally supported by the lever 73 and engages the teeth of the ratchet wheel 70 so that when the rod 72 is turned in one direction the pawl will ride over one or more teeth of the wheel 70 without turning said 30 wheel. This movement occurs, as will presently appear, as the type carriers move to recording position. After printing has been effected the rod 72 is turned back to its initial position and the pawl 74 engaging a 35 tooth of the wheel 70 turns said wheel and thereby the platen to feed the paper in line spacing. A spring 75 connects the tail of the pawl 74 with a projection on the lever 73, thereby holding the pawl in engagement 40 with the wheel 70.

An arm 76 is supported by the rod 72. As shown in Fig. 6, the rod 72 comprises cylindrical portions 72^a and rectangular portions 72^b. The arm 76 has a rectangular opening therethrough so that when said arm is engaged with the rectangular portions 72^b of the rod 72, said rod may be rocked by oscillation of the arm; but when said arm is engaged with the cylindrical 50 portions 72^a the arm will turn upon the rod without turning the rod. As the paper carriage is moved laterally the arm 76 is held from lateral movement with the carriage by a projection 77 in connection with the ease of 55 the machine which permits the arm to be oscillated as required to operate the line space mechanism, but which holds the arm from lateral movement when the paper carriage is moved laterally, thus sliding the 60 arm along the rod 72.

A link 78 has its rear end pivoted to one of the usual oscillating arms 79. It is well known that the arms 79 constitute parts of a bail which controls the operation of the 65 recording mechanism in the Dalton adding

machine, and that said arms 79 are swung forwardly at each forward turning movement of the shaft 26 and are turned rearwardly at each rearward turning movement of said shaft 26. The forward end of the 70 link 76 is formed with a slot 80 which is nearly horizontal for a portion of its length and the forward end of which curves downwardly. A screw 81 supported by the machine frame extends through the slot 80 and 75 supports the forward end of the link 78. The lower end of the arm 77 carries a roller 82 which engages in a notch 83 in the link 78. Since the link 78 is reciprocated at each operation of the recording mechanism, the 80 arm 76 is oscillated at each operation of the recording mechanism.

The carriage shifting mechanism is illustrated in Fig. 2 in position to present the first or left hand column of paper at the 85 recording mechanism. In such position the item will be recorded in the first or left hand column and the paper carriage will be shifted laterally without operation of the line space mechanism, it being understood 90 that the arm 76 is engaged upon one of the cylindrical portions 72^a of the rod 72 when the carriage shifting mechanism is in the position shown in Fig. 2.

From the foregoing it is apparent that 95 the invention fully accomplishes its object. The paper carriage will be moved automatically in alternately opposite directions to different columnar positions; and, when it is desired to record successively, in a single 100 column the carriage shifting mechanism may be rendered inactive by the simple manipulation and adjustment of the stem 41. However, when items or numbers are recorded in different columns the adding 105 mechanism is automatically prevented from functioning as an incident to movement of the paper carriage to one or its columnar positions. Thus, any identifying numbers such, for instance, as car numbers or the 110 like, may be recorded in one column and such numbers will not be added or included in the totals added in the adding pinions.

It is clear that the particular construction and arrangement of the mechanism may be 115 varied without departure from the principle of the invention. I do not restrict myself to unessential features or details of construction, but what I claim and desire to secure by Letters Patent, is:—

1. The combination with a paper carriage, a lever engaging the paper carriage for moving the carriage to different columnar positions, a rotary shaft, a connection for operating said lever from said shaft, mechanism for rotating said shaft, and a link for operating said mechanism, of a rock shaft, an arm attached to and moving with the rock shaft, a lever connecting said arm and said link, arranged to actuate said link as 120 125 130

required to operate said mechanism for rotating said rotary shaft, and means for disconnecting said parts to enable said rock shaft to be operated while said link and the 5 mechanism connected therewith remain stationary.

2. In a machine of the character described, the combination with a laterally movable carriage, a rock shaft, an arm on 10 said rock shaft, mechanism for moving said carriage laterally to different adjusted positions, and a device for actuating said mechanism, of a lever connecting said arm and said device for actuating said device from 15 said rock shaft, and means for disconnecting said device from said lever and holding said parts disconnected to permit said lever to operate while said device remains stationary.

20 3. In a machine of the character described, the combination with a laterally movable paper carriage, a support, and a lever having one end pivoted to said support and the opposite end engaging said carriage, of a 25 shaft, an arm attached to said shaft, a link having one end pivoted to said arm and the opposite end pivoted to said lever between the point at which said lever is pivoted and the point at which said lever engages the paper carriage, a pinion on said 30 shaft, a gear wheel meshing with said pinion, a ratchet device for rotating said gear wheel, a link connected to said ratchet device, a lever connected to said link for reciprocating the same, means for actuating 35 said lever, and means for disconnecting said link from said lever to prevent movement of said link by said lever.

4. In a machine of the character described, 40 the combination with a laterally movable paper carriage, recording devices for printing on paper in the carriage, and a rock shaft determining when the recording devices may be operated, of a revolute shaft, 45 connections between the revolute shaft and the paper carriage, whereby the paper carriage will be moved laterally alternately in opposite directions by intermittent rotation of said shaft in one direction, gearing for 50 rotating said shaft, a ratchet device for actuating said gearing, a link connected to said ratchet device, a lever connected to said link, a connection between said lever and said rock shaft whereby said lever will 55 be operated by said rock shaft, and means for disconnecting said link from said lever to permit said lever to operate independently of said link.

5. In a machine of the character described, 60 the combination with a laterally movable paper carriage, recording devices for printing on paper in the carriage, and a rock shaft determining when the recording devices may be operated, of a revolute shaft, 65 connections between the revolute shaft and

the paper carriage whereby the paper carriage will be moved laterally alternately in opposite directions by intermittent rotation of said shaft in one direction, gearing for rotating said shaft, a ratchet device 70 for actuating said gearing, a link connected to said ratchet device, a lever connected to said link, a connection between said lever and said rock shaft whereby said lever will be operated by said rock shaft, a manipulative device 75 for disconnecting said link from said lever to permit said lever to operate while said link remains inoperative, and construction whereby said device will retain said link disconnected from said lever 80 as long as desired.

6. In a machine of the character described, the combination of a paper carriage, a support, a lever having one end pivoted on said support and the opposite end connected to 85 the paper carriage, a rotary shaft, a connection from the rotary shaft to said lever, a pinion on said shaft, a disk on said shaft, a detent device engaging said disk to prevent accidental rotation of said shaft, a gear 90 wheel meshing with said pinion, a disk attached to said gear wheel, a pawl arranged to engage said last-named disk, a link for actuating said pawl, and means for operating said link.

7. In a machine of the character described, the combination of a paper carriage, a support, a lever having one end pivoted on said support and the opposite end connected to 100 the paper carriage, a rotary shaft, a connection from the rotary shaft to said lever, a pinion on said shaft, a disk on said shaft, a detent device engaging said disk to prevent accidental rotation of said shaft, a gear wheel meshing with said pinion, a disk attached to said gear wheel, a pawl arranged to engage said last-named disk, a link for actuating said pawl, a lever connected with said link for actuating the same, and means for operating said lever.

8. In a machine of the character described, the combination of a paper carriage, a support, a lever having one end pivoted on said support and the opposite end connected to 115 the paper carriage, a rotary shaft, a connection from the rotary shaft to said lever, a pinion on said shaft, a disk on said shaft, a detent device engaging said disk to prevent accidental rotation of said shaft, a gear wheel meshing with said pinion, a disk attached to said gear wheel, a pawl arranged to engage said last-named disk, a link for actuating said pawl, a lever connected with said link for actuating the same, means for operating said lever, an additional lever 120 engaging said link, and means for operating said additional lever to disengage said link from said second-named lever.

9. In a machine of the character described, the combination of a paper carriage, a sup- 130

port, a lever having one end pivoted on said support and the opposite end connected to the paper carriage, a rotary shaft, a connection from the rotary shaft to said lever, a 5 pinion on said shaft, a disk on said shaft, a detent device engaging said disk to prevent accidental rotation of said shaft, a gear wheel meshing with said pinion, a disk attached to said gear wheel, a pawl arranged 10 to engage said last-named disk, a link for actuating said pawl, a lever connected with said link for actuating the same, means for operating said lever, an additional lever engaging said link, and an adjustable device 15 for holding said last-named lever in position to retain said link out of engagement with said second-named lever.

10. In a machine of the character described, the combination of a paper carriage, a rotary shaft, a connection from the rotary shaft to the paper carriage whereby said carriage will be moved alternately in opposite directions by rotation of said shaft, a pinion on said shaft, a gear wheel meshing 20 with said pinion, a disk rigid with said gear wheel, a pawl engaging said disk, a link for operating said pawl, a rock shaft, a lever operated by the rock shaft having pivotal connection with said link for actuating said 25 link, a lever engageable with said link, and a device for actuating said last-named lever to disconnect said link from said first-named lever.

11. In a machine of the character described, 30 the combination of a paper carriage, a rotary shaft, a connection from the rotary shaft to the paper carriage whereby said carriage will be moved alternately in opposite directions by rotation of said shaft, a pinion on said shaft, a gear wheel meshing 35 with said pinion, a disk rigid with said gear wheel, a pawl engaging said disk, a link for operating said pawl, a lever, a spring holding said link in engagement with said lever, and means for operating said lever and 40 thereby said link.

12. In a machine of the character described, the combination of a paper carriage, a rotary shaft, a connection from the rotary 45 shaft to the paper carriage whereby said carriage will be moved alternately in opposite directions by rotation of said shaft, a pinion on said shaft, a gear wheel meshing with said pinion, a disk rigid with said gear 50 wheel, a pawl engaging said disk, a link for operating said pawl, a lever, a spring holding said link in engagement with said lever, means for operating said lever and thereby said link, and a device for moving said link 55 out of engagement with said lever in opposition to said spring.

13. In a machine of the character described, the combination of a paper carriage, a rotary shaft, a connection from the rotary 60 shaft to the paper carriage whereby said 65

carriage will be moved alternately in opposite directions by rotation of said shaft, a pinion on said shaft, a gear wheel meshing with said pinion, a disk rigid with said gear wheel, a pawl engaging said disk, a link for 70 operating said pawl, a lever, a spring holding said link in engagement with said lever, means for operating said lever and thereby said link, a device for moving said link out of engagement with said lever in opposition 75 to said spring, and means for retaining said device in position to hold said link out of engagement with said lever.

14. In a machine of the character described, the combination with a paper carriage 80 shiftable laterally to different adjusted positions, recording mechanism for recording on paper in the paper carriage in any of its lateral adjustments, line space mechanism, and adding mechanism operable 85 by the recording mechanism to add numbers recorded thereby, of means for moving the adding mechanism to inoperative position, a rod supported by the paper carriage for actuating the line space mechanism, a lever 90 slidably supported on said rod, means for oscillating said lever at each operation of the recording mechanism, and construction whereby said lever will actuate said rod in one position of the paper carriage and will 95 leave the rod inoperative in another position of the carriage during operation of the recording mechanism.

15. In a machine of the character described, the combination with a paper carriage 100 shiftable laterally to different adjusted positions, recording mechanism for recording on paper in the paper carriage, adding mechanism operable by the recording mechanism to add numbers recorded thereby, a rock shaft, and connections operated by the turning movement of the rock shaft in one direction to move the adding mechanism to inoperative position, and operated by the turning movement of the rock shaft 110 in the other direction to move the adding mechanism to operable position, of a lever, connections whereby said lever in one position thereof will hold said rock shaft in position to prevent operation of the adding 115 mechanism, and a cam device supported by the paper carriage for moving said lever to position to hold said rock shaft in position to prevent operation of the adding mechanism.

16. The combination with a paper carriage 120 shiftable laterally to different adjusted positions, mechanism for recording on paper in the paper carriage, adding mechanism operable by the recording mechanism to add numbers recorded thereby, a rock shaft, and connections operated by turning movement of the rock shaft in one direction to move the adding mechanism to inoperative position and operated by turning movement of the 125 130

- rock shaft in the other direction to move the adding mechanism to operable position, of a lever, connections from said lever to said rock shaft whereby said lever in one position thereof will hold said rock shaft and said first-named connections in position to prevent operation of said adding mechanism, a cam device on the paper carriage for moving said lever to and holding said lever in position to prevent operation of the adding mechanism, and means for moving said lever to position to permit operation of the adding mechanism when said cam device is moved out of contact with said lever.
- 15 17. In a machine of the character described, a paper carriage, a lever connected with the paper carriage, a rotary shaft, a connection from the rotary shaft for moving said lever alternately in opposite directions
- 20 by the successive rotary movements of said shaft in one direction, a pinion attached to said shaft, a ratchet device, a gear actuated by said ratchet device for rotating said pinion and thereby said shaft, a link connected
- 25 with said ratchet device for operating the same, a lever in connection with said link for moving said link in opposite directions, means for operating said lever, and means for disconnecting said link from said lever.
- 30 18. In a machine of the character described, a paper carriage, a lever connected with the paper carriage, a rotary shaft, connections from the rotary shaft to the lever for moving the lever alternately in opposite
- 35 directions by successive rotary movements of said shaft in one direction, a pinion attached to the rotary shaft, a gear wheel meshing with said pinion, a ratchet member in connection with said gear wheel, a pawl
- 40 for actuating said ratchet member and thereby said gear wheel, a link for operating said pawl, a lever connected with said link for operating the same, means for operating said lever, and means for disconnecting said
- 45 link from said lever to enable said lever to operate independently of said link.
19. In a machine of the character described, the combination with a paper carriage, mechanism for recording on paper in the carriage, mechanism for moving the paper carriage laterally in alternately opposite directions to different columnar positions, a rod in the paper carriage, a lever slidable on said rod and being operable to rock said rod in one columnar position of the paper carriage and being ineffective to rock said rod in another columnar position of the paper carriage, means for actuating said lever, and line space mechanism operated by said rod.
- 50 60
20. In a machine of the character described, a paper carriage, a rockable rod in the paper carriage, line space mechanism operated by the rod, a lever slidably supported on said rod, construction whereby oscillation of said lever will turn said rod in one position of the lever and will leave the rod inoperative in another position of said lever, means for moving the paper carriage laterally, means for sliding the lever on the rod as the paper carriage is moved laterally, recording mechanism for recording on paper in the paper carriage, and means operated as an incident to operation of the recording mechanism for operating said lever.
- 65 70 75
21. In a machine of the character described, a laterally movable paper carriage, recording mechanism for recording on paper in the paper carriage in any of its lateral adjustments, line space mechanism, a rod supported by the paper carriage for actuating the line space mechanism, a lever slidably supported on said rod, means for oscillating said lever at each operation of the recording mechanism, and construction whereby said lever will actuate said rod in one position of the paper carriage and will leave the rod inoperative in another position of the carriage during operation of the recording mechanism.
